UNITED STATES PATENT OFFICE.

ISAAC BOWE, OF CHICAGO, ILLINOIS, ASSIGNOR OF ONE-HALF TO GEORGE A. GINDELE, OF SAME PLACE.

BOILER-FURNACE.

SPECIFICATION forming part of Letters Patent No. 371,872, dated October 18, 1887.

Application filed May 24, 1887. Serial No. 239,187. (No model.)

To all whom it may concern:

Be it known that I, ISAAC BOWE, of Chicago, in the county of Cook and State of Illinois, have invented certain new and useful Improvements in Boiler-Furnaces, of which the following is a description, reference being had to the accompanying drawings, forming a part of this specification, in which—

Figure 1 is a longitudinal sectional view of my improved furnace, including a side view of a boiler inclosed within a suitable setting. Fig. 2 is a vertical sectional view of said boiler and furnace, taken upon the line 2 2, Fig. 1, and viewed in the direction of the arrow there 15 shown. Fig. 3 is a front view in detail of said furnace-door, from which the draft-regulator has been removed. Fig. 4 is an enlarged elevation, in detail, of a portion of the boiler-front, showing my improved automatic appliances 20 for regulating the admission of air above the grate. Fig. 5 is an enlarged side view, in detail, of said automatic regulating apparatus. Fig. 6 is a transverse vertical sectional view, in detail, of said door and a portion of the automatic appliance for regulating the same. Fig. 7 is an enlarged detail view, in section, of 25 my improved dash-pot constituting a part of said regulating mechanism; and Fig. 8 is an enlarged detail view, partly in section, of a 30 portion of the furnace-door and hinge, including the mechanism immediately connected therewith for closing it.

Like letters of reference indicate like parts in the different figures.

It is well recognized among those skilled in the art of building and operating furnaces that in order to save fuel and produce complete combustion the conditions must be such as at all times to supply the relative quantity of air 35 to the fuel to form the proper chemical union and to mingle said air with the evolved gases at a temperature sufficiently high to insure their combination. To accomplish this end various means have been devised for uniformly 40 and continuously feeding the fuel to the furnace, in order that the character of the gases given off may be constant and unchanging and thus proportioned to an even and regular draft. While this has been attended with more or less 45 success in different forms, yet objections have

been found, among others, that the cost of preparing the fuel for proper continuous feeding has been so great as to render this method undesirable, while without such preparation it is more or less impracticable to maintain an even and thin fire over the entire grate, so as to uniformly heat the boiler.

My invention has for its object to overcome these difficulties and to so construct a boiler-furnace, in combination with suitable automatic appliances, that the same may be fed at intervals in the usual way, and that by means of said automatic appliances a volume of air, or air and steam, may be admitted to the fire above the grate in sufficient quantity to properly commingle and chemically combine with the more volatile hydrocarbon gases first evolved, and to be gradually decreased or shut off in proportion as the demand therefor becomes lessened or ceases to exist, so that what are known as "cooling drafts" of air may be prevented.

A further object is to so arrange and construct the bridge-wall of said furnace with reference to the grate and boiler-shell that a sufficient degree of heat may be maintained at all times to complete the combustion of the gases before the products thereof are admitted to the boiler-flues, while at the same time the heat in contact with the boiler-shell is rendered uniform throughout its entire length, which permits said shell to expand evenly, thus preventing the straining of the seams and obviating a well-known cause of explosion. Moreover, I desire to so construct said furnace 55 as to prevent the formation of eddies therein.

I accomplish said objects substantially in the manner hereinafter more particularly described, and definitely pointed out in the claims.

In the drawings, A represents the furnace wall or setting, while B is an ordinary tubular boiler supported therein in the usual way.

C represents a grate of any approved form, which is preferably somewhat inclined toward 95 the rear.

D indicates a bridge-wall, the main portion of which I construct at or about the height of the grate, from whence it is carried back to the rear of the boiler, as clearly shown in Fig. 1. 100

At or about a distance of one-quarter or one-third of the length of the grate (more or less) I build up a portion, D', Fig. 2, of said bridge-wall in the form of an inverted arch, which is preferably about the thickness in proportion to the length of said bridge-wall, as indicated in Fig. 1. A space, E, Figs. 1 and 2, uniform in width, is provided for the passage of the heat between the bridge-wall and boiler-shell, while said wall is pierced with two or more tubular flues, F, through which the main portion of the products of combustion pass, and which are intended to concentrate the heat, and serve, in connection with other appliances, hereinafter described, to complete the combustion of the gases. The number and size of said flues should vary in proportion to the area of the boiler-tubes. A space, D², between the rear of the grate and the beginning of said combustion-flues, is provided, in order that the oxygen of the air admitted above the grate may thoroughly commingle with the gases before the latter have time to escape to the flues and thus pass off unconsumed. I provide two or more tubular openings, G, Fig. 1, corresponding in number to the flues in the bridge-wall and directed toward the same, respectively, into which I insert steam-jet nozzles G', Figs. 1 and 5, which are smaller than the tubes G, so that an annular space is left around the former for the admission of air to the furnace. The nozzles G' are connected with a steam-pipe, G², in direct communication with the boiler. The flow of steam in said pipe is regulated by a valve, G³, which is operated in the manner hereinafter described.

H is a cylinder or dash-pot loosely suspended from a bracket, h, which permits said cylinder to swing in the arc of a circle. Said cylinder is provided with a piston, H', Fig. 7, having an opening, h', therein, which is covered upon the under side of the piston by a check-valve, h². To said cylinder is attached a hollow piston-rod, H², open at the top, but closed at the bottom by a screw-cap, h³, to which is loosely attached a small supplemental piston-rod, J, attached to a loose piston, J', within said tube. Said rod should be so attached to the cap h³ that the screwing or unscrewing of the latter may serve to gradually move the piston up or down, so as to wholly expose or cover an opening, h⁴, within said tube. Upon the lower end of the piston-rod H² is attached a ring, h⁵, which is in turn loosely secured to a sleeve, k, mounted upon an arm, K, rigidly attached to a rock-shaft, K', extending across the furnace-front and secured in bearings k' k', Fig. 4. The sleeve k is adjustable upon the arm K, and is secured in any desired position thereon by means of a set-screw, k², so that the extent to which the shaft is rotated by the movement of the piston may be varied.

The cylinder H is filled with water, oil, or other liquid, and a weight, H³, is attached to the piston-rod to draw the piston down. Ad-

justable collars g g' are likewise attached to said piston-rod by means of set-screws, said collars being provided with projecting pins g² g³, Figs. 4 and 5, which serve to engage with and operate an arm, G⁴, connected with the stop-cock G³. The extent of movement of said arm, and in turn of said stop-cock, is varied by the position of the pins with relation thereto, so that the valve may be wholly or partially opened or closed, accordingly as the pins are adjusted and the piston-rod reciprocated.

L L are the upper and L' L' the lower furnace-doors. The draft through the latter is 80 constantly more or less open to supply air beneath the grate; but that in the former is varied in proportion to the demand therefor to properly support combustion. Each of said main doors L is provided with an inner perforated portion, L², and an outer supplemental door, L³, mounted upon trunnions, and having one side, as l, Fig. 6, made heavier than the other, so that its tendency is to open by virtue of its own gravity. Rods l' l', loosely pivoted to said supplemental doors and extending upwardly through perforations l' l', are arranged to engage with arms K² K², adjustably attached to the rock-shaft K'. Rollers l' l' are provided to prevent friction.

The rock-shaft K' is provided with bevel-gears M M, which mesh into like gears M' M', having sleeves m loosely mounted upon the pintles m² m², Fig. 8, of the door-hinges l' l'. Loose rings N N are mounted upon each of said sleeves, to which are rigidly attached arms N' N', having friction-rollers n n upon their free ends, adapted to engage with the doors L. A stud, m³, is formed upon each of the sleeves m, which is normally adapted to engage with a shoulder, n', upon the ring, so that as the door L is opened the gear M' is caused to rotate. By means of handles n² n² the arms N' and ring N may be lifted, so that the shoulder and pin are disengaged, when the doors L may be opened without actuating the gears M'. Said handles likewise form stops for limiting the backward movement of the doors when opened. The supplemental doors L² are provided, also, with adjustable stops L⁴, which are secured to the door by means of thumb-screws, and are provided with slots, whereby they may be moved up and down, thus limiting the extent to which the door L² may be opened.

The operation of said mechanism is as follows: When a fresh charge of coal is supplied to the furnace, it is obvious that a large volume of volatile gas is at once given off. This requires a much greater proportion of air above the grate to insure combustion than is necessary for the fixed carbons. Upon opening the door the gears M M' are rotated by means of the arm N' and the arms K² are tilted, which permits the gravity-doors L² to fall open to their utmost limit. At the same time the arm K is also tilted, which raises the piston H' to

the top of the dash-pot and opens the cock G^3 , thus permitting the steam-jets to operate through the openings G . The liquid in the dash-pot passes through the check-valve below the piston; but the weight H^3 tends to draw the piston down and to force the liquid through the opening h^3 above the piston, which moves down slowly according to the speed with which said liquid is permitted to pass through said opening, the action thereof being regulated by means of the screw-cap h^3 . Thus the valve G^3 is slowly closed, while the rock-shaft is reversed and the arms K^2 , engaging with the rollers upon the rods l' , gradually close the supplemental doors, thus decreasing the supply of air in regular proportion as the hydrocarbon gases are evolved.

If it is desired to open the door without operating the automatic mechanism, the handle n^2 may be lifted, as described. The extent to which the valve G^3 is opened may also be governed by the position of the pin g^3 , which may be moved down sufficiently, so that the valve need not be opened at all.

The openings G are placed opposite to the flues F , and as the air or air and steam from said openings and the air from the door L commingle with the gases before reaching the flues F , and while said gases are at a temperature above the combustion-point, it is obvious that a complete chemical combination must ensue. Were this otherwise complete combustion could not be obtained, as it is well known that the highest temperature of the boiler is but about one-half of that required for ignition and one-third of that for complete combustion. As soon, therefore, as the heated gases are brought into direct contact with the boiler shell or flues, a sufficient degree of heat is absorbed therefrom to reduce the heat of said gases below the point of combustion, when no further chemical change can take place. By providing the space D^2 , however, and concentrating the heat immediately in front of and within the flues F , at which points the air is directed, a complete combustion is obtained, as stated.

The space E permits a portion of the heat to pass between the boiler-shell and bridge-wall, so that said boiler is uniformly heated throughout its entire length. The bridge-wall D , being built back to the rear end of the boiler, fills the space usually employed as a "combustion-chamber," and entirely prevents the formation of eddies, which greatly interfere with the draft, and to that extent impede the action of the furnace.

Having thus described my invention, what I claim, and desire to secure by Letters Patent, is—

1. The combination, in a boiler-furnace, of a bridge-wall, the main portion of which is constructed at or about the height of the grate and carried back to the rear of the boiler, a raised portion in the form of an inverted arch and provided with combustion-

flues and a draft-space between its top and the boiler-shell, and a space between its front and the rear of the grate, with means for introducing a volume of air above the grate, substantially as and for the purposes set forth.

2. The combination, in a boiler-furnace, of a bridge-wall, the main portion of which is constructed at or about the height of the grate and extended to the rear of the boiler, a higher portion extending upward and conforming to the shape of the boiler, with a sufficient space between the two to permit the ready passage of heat, a space between the rear of the grate and said raised portion, combustion-flues piercing said raised portion, and means for automatically introducing a large volume of air above the grate upon charging the furnace and for gradually reducing said air-supply, substantially as and for the purposes set forth.

3. The combination, with a furnace, of the dash-pot H , substantially as described, and intermediate mechanism for connecting its piston-rod with the door or doors of said furnace, and gravity draft-regulating supplemental doors, whereby the opening of a main door may raise the piston of said dash-pot, substantially as and for the purposes set forth.

4. A dash-pot consisting of a hollow cylinder provided with a perforated piston having a check-valve and tubular piston-rod, the latter being provided with a small perforation at or near its upper end, and means for partially closing said perforation, in combination with means for operatively connecting said piston-rod with the main and supplemental doors of a furnace, substantially as and for the purposes set forth.

5. In an automatic mechanism for regulating the draft of furnaces, the combination of the doors L , having supplemental gravity-doors mounted in trunnions therein and provided with rods l' , a rock-shaft geared to the hinges of said doors and connected by an arm, K , to the piston-rod of a dash-pot, and oscillating arms arranged to engage with the rods l' , for closing the supplemental doors upon the movement of said rock-shaft, substantially as and for the purposes specified.

6. The combination, with a furnace provided with a pipe for injecting steam, and gravity-doors for admitting air above the grate, of a stop-cock in said pipe connected by an arm with the piston-rod of the dash-pot H , a rock-shaft in operative connection with said piston-rod, arms thereon adjusted to engage with rods loosely attached to said gravity-doors, and gears for connecting said rock-shaft to the hinges of the main doors, substantially as and for the purposes set forth.

7. The combination, with the door L and sleeve m , having a stud upon its lower end, of the adjustable ring N , having an arm, N' , in normal engagement with the face of said door, whereby said ring may be raised and the door opened without operating said au-

tomatic draft mechanism, substantially as specified.

8. The combination, with a furnace-door, of the supplemental gravity-door L^3 , the normal tendency of which is to remain open, and the dash-pot with intermediate mechanism for gradually closing the same after charging

the furnace, substantially as and for the purposes set forth.

ISAAC BOWE.
